(57) **CLAIM**

The ornamental design for an iron golf club head cavity, as shown and described.

DESCRIPTION

FIG. 1 is a heel side, back perspective view of our new iron golf club head cavity;

FIG. 2 is a back view thereof;

FIG. 3 is a top, back perspective view thereof; and,

FIG. 4 is a toe side, back perspective view thereof.

The portion of the iron golf club head cavity shown in phantom does not form any portion of the present invention.
